UNITED STATES PATENT OFFICE

FRITZ G. CORNELL, JR., OF MOUNTAIN LAKES, NEW JERSEY

SURFACE COOLER AND HEATER

Application filed September 26, 1930. Serial No. 484,532.

This invention relates to surface coolers or heaters and more especially to devices of this character for treating dairy products.

A common type of surface cooler or heater for dairy products comprises a plurality of superposed horizontal pipes serially connected, through which cooling or heating fluid is caused to flow. Above the top pipe is provided a trough or pipe having a series of perforations, through which the dairy product drops on to the top pipe and thence flows over the remaining pipes. In such devices, the distribution of the dairy product over the pipes is not always uniform and the clogging of any of the apertures with sediment or foam renders the distribution less uniform and also reduces the total flow of the dairy product.

An object of this invention is a distributor for surface heaters or coolers by which the liquid is uniformly distributed over the pipes and the rate of flow is maintained substantially uniform in spite of sediment or foam.

Other objects, novel features and advantages of this invention will be apparent from the following specification and accompanying drawing, wherein:

Fig. 1 is an end elevation of a device embodying the invention.

Fig. 2 is a section on the line 2—2 of Fig. 1.

Fig. 3 is a section on the line 3—3 of Fig. 2.

Fig. 4 is a fragmentary plan view, and

Fig. 5 is a section on the line 5—5 of Fig. 4.

A plurality of superposed serially connected pipes 10 constitute the heating or cooling member which is supported by brackets 11 from vertical posts 12. The structure, arrangement and means of support of these pipes may be any of the forms well-known in the art.

A trough of the usual type is supported by the bottom brackets 11 for receiving liquid which has flowed over the pipes 10. A bracket 14 is supported by each post 12 and is provided at its free end with an elongated

slot 15. A bolt 16 threaded at each end extends through this slot and carries semi-spherical members 17, the faces of which engage the top and bottom surfaces of the bracket 14. Washers 18 are also carried by the bolts 16 and have recesses into which the curved portions of the members 17 project. Nuts 19 are threaded on the bolt 16 and comprise means for clamping the bolt and the members carried by the bolt to the bracket. 55

A cradle 20 is supported by the upper end of each bolt 16. The cradles 20 receive lugs 21 projecting from the end faces of a trough 22 which is supported by the cradles. The trough comprises a curved plate 23 which forms one side wall and a flat vertical plate 24 which forms the other side wall. The vertical plate 24 is connected at its bottom edge to the curved plate 23 which extends beyond the plate 24 to form a lip or apron 25. The ends of the trough are formed by plates 26 which extend beyond the plate 24 to form end walls for the apron 25. The vertical wall 24 is of less height than the curved wall 23 and the end plates 26 and is provided with a plurality of superposed horizontal rows of apertures 27 which are preferably of progressively larger area upwardly. The bottom row of holes is spaced slightly from the bottom of the wall 24 and one or more drainage apertures 28 are provided as close as possible to the bottom of the wall 24. 75

The trough 22 is adjustable so that its position relative to the pipes 10 may be varied as desired. By reason of this adjustable feature, it is possible to arrange the edge of the lip 25 directly over the top pipe 10 so that the liquid stream will divide equally on to the opposite sides of the collar. Also, the trough may be maintained accurately horizontal, although the pipes may have been moved slightly out of horizontal by reason of sagging of the floor and the like. Also, the trough may be tilted as desired to vary the slope of the apron 25. These ad- 85 90

justments are accomplished by means of the bolt 16 and the members carried thereby. Either end of the trough may be raised or lowered by proper adjustment of the nuts 19. The trough may be moved horizontally by loosening the nuts 19 and move the bolt 16 in the slot 15. In a similar manner, the trough may be tilted by angular movement of the bolt in the semi-spherical members 17. In the use of this apparatus, liquid dairy product is introduced into the trough 22 at a rate of flow greater than can be discharged by the lower row of holes 27, but preferably less than can be discharged by all of the rows of holes 27. Liquid will therefore flow out of the requisite number of rows of holes. The liquid upon striking the apron 25 is spread out into a thin sheet of uniform thickness which extends down to the top pipe 10, thereby supplying the dairy product uniformly to the entire length of such pipe. Should a number of the holes become clogged, the uniformity of distribution will not be affected materially, due to the action of the apron 25 and if there is any lack of uniformity it will quickly be overcome due to the fact that the level of the liquid in the trough will rise sufficiently to discharge through the next row of holes. Also, the rate of flow will remain substantially uniform although it may be reduced temporarily while the level of the liquid is rising to the level of the next series of holes. The possibility of overflow of dairy products from the apparatus due to clogging of the apertures is eliminated by the fact that the wall 24 is of less height than the remaining walls. Should the trough become filled, the liquid will escape over the edge of the wall 24 and flow on to the apron 25 by which it will be directed to the cooler. The apron effects blending of the individual streams of liquid before they reach the cooling or heating surfaces and causes delivery of the dairy product at a minimum velocity, thereby minimizing splashing. The foam or froth forming on the surface of the dairy products and not flowing through the apertures will escape over the top of the vertical wall 24 and mix with the liquid on the apron. Uniform and even flow and distribution of the product are effected by the apron regardless of the volume of flow. Either hot or cold liquid products may be treated by this apparatus. By adjustment of the supporting means for the trough its position relative to the pipes may be altered to locate the end of the apron directly over the pipes and in the relation best adapted to produce a uniform layer of liquid over the surfaces of the pipes. The trough is sanitary and easy to clean and may be easily removed and accurately replaced. It is of course to be understood that various modifications may be made in the device above disclosed without in any way depart-

ing from the spirit of the invention as defined in the appended claims.

I claim:

1. A trough adaptable for the distribution of liquid over a surface cooler and having a side wall of less height than the remaining side and end walls, means for supporting said trough above said surface cooler for horizontal, vertical and tilting adjustment of the trough, a plurality of superposed rows of holes in the wall of less height, an apron extending therefrom below the bottom row of holes for spreading liquid escaping through said holes into a stream of uniform depth, and walls at the lateral edges of the apron. 70

2. A trough adaptable for the distribution of liquid over a surface cooler and having a side wall of less height than the remaining side and end walls, means for supporting said trough above said surface cooler for horizontal, vertical and tilting adjustment of the trough, said side wall of less height being provided with a plurality of superposed rows of holes, an apron extending therefrom below the bottom row of holes for spreading liquid escaping through said holes into a stream of uniform depth, and walls at the lateral edges of the apron. 85

3. A trough adaptable for the distribution of liquid over a surface cooler, and means for supporting said trough for vertical, horizontal and tilting adjustment, said means comprising a pair of horizontal brackets having vertical slots, a threaded bolt engaging the trough and extending through each slot, blocks engaging the upper and lower faces of each bracket and having rounded portions, additional blocks having recesses receiving said rounded portions, both sets of blocks having apertures through which said bolts extend, and nuts on each bolt engaging the last named blocks. 95

4. A trough adaptable for the distribution of liquid over a surface cooler, having a side wall of less height than the remaining side and end walls, a plurality of superposed rows of holes in the wall of less height, an apron extending therefrom below the bottom row of holes for spreading liquid escaping through the holes into a stream of uniform depth, walls at the lateral edges of the apron, and means for supporting said trough for vertical, horizontal and tilting adjustment, said means comprising a pair of horizontal brackets having vertical slots, a threaded bolt engaging the trough and extending through each slot, blocks engaging the upper and lower faces of each bracket and having rounded portions, additional blocks having recesses receiving said rounded portions, both sets of blocks having apertures through which said bolts extend, and nuts on each bolt engaging the last named blocks. 110

5. A trough adaptable for the distribution of liquid over a surface cooler, means for sup- 120 125 130

porting said trough above said surface cooler for horizontal, vertical and tilting adjustment of the trough, a row of holes in one wall of said trough and an apron extending from the trough below the row of holes for receiving liquid escaping through said holes and delivering the same to said cooler in a stream of uniform depth.

In testimony whereof, I have signed my
10 name to this specification.
